INVENTOR:

Nathaniel P. Sheldon,
By his Atty. J. Dennis Jr.

UNITED STATES PATENT OFFICE.

NATHANIEL P. SHELDON, OF SAN FRANCISCO, CALIFORNIA, ASSIGNOR TO
HENRY H. WELCH, OF SAME PLACE.

IMPROVEMENT IN PUMP-PLUNGERS AND PUMPS.

Specification forming part of Letters Patent No. 140,795, dated July 15, 1873; application filed
June 2, 1873.

To all whom it may concern:

Be it known that I, NATHANIEL P. SHELDON, of the city and county of San Francisco and State of California, have invented certain new and useful Improvements in Pumps; and I do hereby declare the following description and accompanying drawings are sufficient to enable any person skilled in the art to make and use my said invention or improvement, without further invention or experiment.

The nature of my invention consists in the particular construction, combination, and arrangement of devices forming the improvements described in the following specification and represented in the accompanying drawings.

Figure one (1) is an elevation of a machine embodying my invention. Fig. two (2) is an elevation of a plunger embodying that portion of my invention connected therewith. Fig. three (3) is an elevation of a valve embodying that portion of my invention connected therewith. Fig. four (4) is an elevation of the head-piece embodying that portion of my invention connected therewith. Fig. five (5) is a vertical transverse section, showing those parts of the machine which would be cut by a horizontal line drawn vertically through its center.

A is the plunger; B, a valve-seat cast with it; B', a detachable valve-seat giving access to the chamber C, in which the valve D plays. E is a discharge-pipe cast with, or otherwise attached to, the plunger. F is an air-chamber attached to the pipe E at a point as near as practicable to the plunger. The valve D has a port, G, corresponding in size to the bore of pipe E. The head-piece H', forming the top of the pump, furnishes a valve-seat, B'', through the ports of which water passes into the chamber opened by the downward stroke of the plunger, the upper portion H of the head-piece, through which the suspension-

rods I pass, is made to fit as closely as practicable to the pipe of the well in which the pump is suspended. K is a packing of leather, rubber, or other material, for preventing the passage of water between the head-piece H and the well-pipe L. The stuffing-box M is for packing around the discharge-pipe. N is a plug for closing an opening in the head-piece, through which the water may be returned to its natural level by raising the plug. B''' is a valve-seat with ports for the reception of water to the lower part of the pump. O is the driving-rod; P, the cylinder. Upon the upward stroke of the plunger the valves D and C', covering the ports in the valve-seats B' and B'', are closed by pressure from the discharge upon their respective valves; and the water above the plunger is forced through the ports of the valve-seat B into the chamber C, and thence into the discharge-pipe E; at the same time the opening space between the valve-seats B' and B''' is being filled through the ports in B'''. Upon the downward stroke the ports in valve-seat B and B''' are closed by pressure from the discharge, and the water below the plunger is forced through the ports in the valve-seats B' to the chamber C, and thence through the port G in the valve D to the discharge-pipe.

I claim—

1. In combination with the cylinder P, plunger A, and hollow rod E, the head-piece H and rods I, for holding the cylinder in the well, pipe or tube L, the whole being constructed and arranged to operate substantially as described.

2. The head-piece H, provided with a stuffing-box M for the hollow rod E and a hub, to connect it to the head of the cylinder P, substantially as described.

NATHANIEL P. SHELDON.
